DESIGN FOR A BED JACKET

Margot E. Smith, Minneapolis, Minn., assignor to Kickernick, Inc., Minneapolis, Minn., a corporation of Minnesota

Application April 19, 1947, Serial No. 138,496

Term of patent 7 years

(Cl. D3—3)

To all whom it may concern:

Be it known that I, Margot E. Smith, a citizen of the United States, residing at Minneapolis, in the county of Hennepin and State of Minnesota, have invented a new, original, and ornamental Design for Bed Jacket, of which the following is a specification, reference being had to the accompanying drawings, forming part thereof.

Figs. 1 and 2 of the drawings are front and rear elevational views, respectively, of a bed jacket, showing my new design.

I claim:

The ornamental design for a bed jacket, as shown.

MARGOT E. SMITH.
